UNITED STATES PATENT OFFICE.

EDWIN NORTON, OF MAYWOOD, ILLINOIS, ASSIGNOR TO THE NORTON BROS., OF CHICAGO, ILLINOIS.

SHEET-METAL CAN.

SPECIFICATION forming part of Letters Patent No. 618,518, dated January 31, 1899.

Application filed October 7, 1897. Serial No. 654,335. (No model.)

To all whom it may concern:

Be it known that I, EDWIN NORTON, a citizen of the United States, residing in Maywood, in the county of Cook and State of Illinois, 5 have invented a new and useful Improvement in Sheet-Metal Cans, of which the following is a specification.

My invention relates to improvements in sheet-metal cans or vessels, and more particularly to improvements upon the sheet-metal can or vessel shown and described in the pending application of myself and Bernard H. Larkin, Serial No. 649,696, filed August 27, 1897, and in which the cover is secured 15 to the can-body both by a vacuum or atmospheric-pressure seal and by a mechanical seal, consisting in crimping an inner upright flange on the can-cover outwardly under and against an inwardly-projecting roll or shoulder at the 20 upper end of the can-body, and in which the can-body has an externally-projecting shoulder to serve as a fulcrum for prying off the cover of the can.

The object of my present improvement is 25 to remove certain defects or objections in the can shown and described in said application and to perfect the same and adapt it for use for preserving fish, meats, fruits, vegetables, or other articles requiring perfect hermetic- 30 ally-sealed vessels for their preservation.

One objection or difficulty experienced with the can shown and described in said application, Serial No. 649,696, is that sometimes the pressure exerted upon the packing-ring 35 interposed between the cover and the can-body would shear or press off a thin annulus or portion of the packing and force it into the can, where it would remain as a deposit on top of the goods in the can, thus injur- 40 ing the same either in quality, appearance, or salability. By my present invention I overcome this difficulty by a peculiar construction of the annular channel or receptacle in the cover for the packing in connection with 45 the roll or shoulder on the can-body, with which it coöperates.

In the can shown and described in said application, Serial No. 649,696, the externally-projecting shoulder or fulcrum on the can- 50 body for prying off the cover is formed by making an integral fold in the stock of the

can-body itself. This occasions two objections or difficulties, especially in cans designed for holding hermetically-sealed food products, viz: First, the sharp fold formed in 55 the stock of the can-body itself is liable to cause slight cracks or breaks in the stock, which may sooner or later develop into pin-holes or fine leaks, so that the cans cannot be as safely relied upon to be perfect or abso- 60 lutely hermetically tight with that certainty and uniformity in every instance which is necessary or desirable in cans used for putting up hermetically-sealed food products, because in such cans a very few—say five or six—leaky or 65 imperfect ones out of one thousand would render that construction of can unfit for such use and impracticable, as is well known to those skilled in the art, and, second, the sharp fold in the body of the can forming the fulcrum 70 leaves a crevice on the inside of the can-body right at the point where the stock is bent or folded, and the tin coating of the tin-plate consequently stretched, tending to give an opportunity for the acids of the food or other 75 products in the can to attack the iron or steel plate from which the tin-plate is formed by coating it with tin, which action is liable to injure the quality, flavor, appearance, or salability of the goods. These two objections or 80 difficulties in the can of said application I overcome or remove in my present invention by providing the can-body at its upper end with a seamless ring, having at its upper edge an internal roll or fold which fits or hooks 85 over the upper end of the can-body and constitutes the inwardly-projecting roll or shoulder for the can, which seamless ring fits outside the can-body and is itself provided with the externally-projecting fold to serve as the 90 fulcrum for prying off the cover. By this means the stock of the can-body itself is left entirely smooth and unfolded, so that the can has a smooth interior surface and so that the stock of the can-body is entirely free from 95 sharp bends or folds which might be liable to cause leaks. The seamless ring also avoids any unevenness caused by the side seam of the can-body in the can of said application, and thus gives a smoother, better, and more 100 perfect seat for the packing between the cover and can, and also for the metal-to-metal con-

tact between the inner flange of the cover and the shoulder or roll at the mouth of the can when said inner flange is forced or crimped out under and against the same.

5 The nature, construction, and operation of my improvement will be more fully understood by those skilled in the art by reference to the accompanying drawings, which form a part of this specification.

10 In said drawings, Figure 1 is a side elevation of a can embodying my invention. Fig. 2 is a central vertical section showing the cover separate from the can and ready to be applied thereto. Fig. 3 is a similar section 15 showing the cover sealed and secured to the can-body by the vacuum or atmospheric seal and before the cover is mechanically sealed or secured in place. Fig. 4 is a similar section showing the cover sealed and secured on 20 the can both by the vacuum or atmospheric-pressure seal and by the mechanical seal. Fig. 5 is an enlarged detail sectional view of the cover to more clearly show the particular construction of the annular channel or seat 25 for the packing, and Fig. 6 is an enlarged detail sectional view of the finished and sealed can to better show its construction and operation.

30 In the drawings, A represents the can-body; B, the cover; C, the rubber, cement, or other packing inserted between the cover and the can-body; D, the bottom of the can, and F the seamless ring.

35 The can-body A may be and preferably is of a plain, smooth, cylindrical form, as illustrated in the drawings, having the customary side seam a.

40 The cover B has an outer upright flange b, which fits outside the can-body, and an inner secondary flange b', which is also substantially upright or at right angles to the plane 45 of the cover. Between the flanges b b' is the annular channel or seat b² for the packing C, the horizontal flange b³ forming the upper wall or bottom, so to speak, of the annular 50 channel or groove b². The inner corner b⁴ of the channel b² is made curved or rounding, while the outer corner b⁵ thereof is made substantially square and preferably about as indicated in Figs. 5 and 6. The packing C may 55 preferably be originally placed chiefly in this outer corner, as indicated in Fig. 5. When the packing C is compressed between the cover and the roll or shoulder at the upper end of the can-body, this enlarged outer corner b⁵ gives room for the compressed packing, and thus prevents any danger of the thin edge or ring of the packing being forced down into the can. The inner flange b' of the cover 60 B has an outwardly-projecting bend or crimp b⁶ in the finished or sealed can, which projects under the inwardly-projecting roll or shoulder at the upper end or mouth of the can-body, and thus mechanically seals and 65 secures the cover on the can, as will be hereinafter more fully explained. The outer flange b of the cover is provided with an ex-

ternally-projecting bend, fold, or shoulder b⁷, which coöperates with the external shoulder or fulcrum on the can-body in opening 70 the can or prying off the cover. The external flange b of the cover preferably projects below this external shoulder b⁷, so as to give greater depth to this external flange of the cover, and thus enable the cover to be more 75 straightly, squarely, and properly guided home on the can-body in the operation of instantaneously forcing the cover home by the suddenly-restored atmospheric pressure in making the vacuum or atmospheric-pressure 80 seal of the can. In this operation of forming the vacuum or atmospheric-pressure seal unless the cover is properly guided and moved to place squarely and truly the vacuum-seal will not be perfectly and properly formed. 85

The bottom or lower head D of the can is or may be of substantially the same construction as that shown and described in said application. It has an external flange d and an annular bead d'.

90 The seamless ring F is provided with an inwardly-projecting fold or roll f, which fits over the upper end of the can-body A, and thus forms or constitutes the inwardly-projecting roll or shoulder at the mouth or upper 95 end of the can-body. As the ring F is seamless, the shoulder or roll f is likewise of course seamless, and thus affords a smooth and perfect bearing not only for the packing C, but also for the metal-to-metal contact between the 100 outward crimp or bend b⁶ in the inner flange b' of the cover and the under or lower part of said roll or shoulder f. The seamless ring F is further provided near its lower edge with an exteriorly-projecting fold or shoulder f', 105 which serves as the fulcrum for prying off the cover by inserting any suitable instrument between said fold, shoulder, or fulcrum f' and the external shoulder b⁷ on the outer flange b of the cover B, as will be readily understood from the drawings. The seamless ring F is soldered to the can-body and serves to materially reinforce and strengthen the same, and thus better adapt the can to withstand both the external or atmospheric pressure due to the vacuum or atmospheric-pressure seal of the can and also any internal 115 pressure that may be due to the cooking or processing of the contents of the can while it is in a hermetically-sealed condition. 120

125 In operation or method of use after the can is filled the cover B is loosely placed thereon, the air is then exhausted from the can by placing it within the receiver of an air-pump, the cover is then hermetically sealed and secured to the can-body by suddenly restoring the atmospheric pressure, thus instantaneously forcing the cover home on the can-body and compressing the packing C between the cover and the inwardly-projecting roll or shoulder f at the upper end or mouth of the can-body. The cover B is then mechanically sealed and secured to the can-body by forming the outwardly-projecting bend or crimp 130

*b*⁶ in the inner flange *b'* of the cover B, as illustrated in Figs. 4 and 6, thus mechanically securing the cover on the can and mechanically holding the packing C in a compressed form. The cover is thus sealed and secured to the can by a double seal, the vacuum or atmospheric-pressure seal and a mechanical seal. The can is opened by placing a suitable instrument between the external fulcrum *f'* on the can-body, or, rather, on the seamless ring which is secured to the can-body and forming a part thereof, and the external shoulder *b'* on the outer flange *b* of the cover.

15 I claim—

1. In a sheet-metal can or vessel, the combination with a can-body of a seamless ring fitting outside the can-body and having an internal roll or shoulder at its upper edge fitting over the upper end of the can-body, and an externally-projecting fold or shoulder at its lower edge to serve as a fulcrum in prying off the cover, and a cover having an outer flange provided with an external shoulder 25 to coöperate with said external shoulder or fulcrum on said seamless ring, said cover having also a secondary inner flange bent or crimped outwardly under and against said internal roll or shoulder at the upper edge of 30 said seamless ring, substantially as specified.

2. The combination with a can-body, of a seamless ring secured to the can-body and provided at its upper edge with an inwardly-projecting roll or shoulder, and a cover having an outer flange and a secondary inner 35

flange bent or crimped outwardly under and against said internal roll or shoulder on said seamless ring, said seamless ring being also provided with an outwardly-projecting fold or shoulder near its lower edge, and the outer 40 flange of said cover having also an outwardly-projecting shoulder and a straight or cylindrical portion below said shoulder, substantially as specified.

3. In a sheet-metal can or vessel, the combination with a can-body of a seamless ring fitting outside the can-body and having an internal roll or shoulder at its upper edge fitting over the upper end of the can-body, and an externally-projecting fold or shoulder at 45 its lower edge to serve as a fulcrum in prying off the cover, and a cover having an outer flange provided with an external shoulder to coöperate with said external shoulder or fulcrum on said seamless ring, said cover 50 having also a secondary inner flange bent or crimped outwardly under and against said internal roll or shoulder at the upper edge of said seamless ring, said cover having an annular channel or seat for a packing between 55 its said outer and inner flanges provided with a curved or rounded inner corner and a square or enlarged outer corner, and a packing in said receptacle or seat, substantially as specified.

EDWIN NORTON.
